UNITED STATES PATENT OFFICE.

WILLIAM BLACKNELL CROSSLAND, OF PHILADELPHIA, PENNSYLVANIA.

LIQUID RHEOSTAT.

Application filed October 13, 1922. Serial No. 594,318.

To all whom it may concern:

Be it known that I, WILLIAM B. CROSSLAND, a citizen of the United States, residing at Philadelphia, in the county of Philadelphia and State of Pennsylvania, have invented a new and useful Liquid Rheostat, of which the following is a specification.

My invention relates to a liquid rheostat, which is automatically operated upon the closing of a switch in the circuit to increase the flow of current gradually until the maximum is reached.

When used in connection with tungsten lamp circuits, my invention prevents the violent jerk to the filament which is caused whenever the full current is turned on suddenly. When used in connection with a motor, it compels a slow and even start, protects the fuses, and reduces starting trouble to a minimum. It also acts as a cut-out when the voltage in the circuit falls below a certain predetermined point.

The general object of my invention is to provide a rheostat which will accomplish the results outlined above, which will be reliable in operation and inexpensive to manufacture, which may be cut into the circuit at any point, and controlled by a switch which may be located at a remote point, and which, when once installed, will require no further attention for many years.

My invention will be best understood from the following description, taken in connection with the accompanying drawing, which illustrates one way in which the invention may be carried out.

In the drawing—

Fig. 1 is a side elevation of the invention;

Fig. 2 is a rear elevation thereof;

Fig. 3 is a vertical longitudinal section on the line 3—3 of Fig. 2;

Fig. 4 is a plan view of the invention.

In carrying out my invention, I provide a jar 1, preferably of glass, and provided with a cover 2 which is made substantially airtight. Secured to the rear side of the jar is a shelf or bracket 3, on which are supported a pair of electro-magnets 4 and 5, the shelf 3 being supported by means of a shoulder 6 in close contact with the rear side of the jar, and ears or brackets 7 which extend along the sides of the jar and are secured to a spindle 8 that extends through the jar and is cemented to the side walls thereof. The spindle within the jar

is enlarged to form a core 9, which is preferably square in cross section, and composed of soft iron surrounded by a thin jacket 10 of brass or other non-corrosive material, and which forms an electrode. The other electrode 11, composed of iron, is secured to the lower edge of a conducting element 12 which is shown in the shape of a quadrant secured to a sleeve 13, loosely mounted on a spindle 14, extending across and secured to the walls of the jar. The element 12 is normally held in the position shown in Fig. 1, by means of a flexible cord 15, or the like, which is wound around the sleeve 13, and passes therefrom upwardly through an opening 12^a in the element 12, and is secured at its upper end to the end of the stem 16 above the jar. When the stem 16 is lowered, the element 12 will gravitate downwardly to the position shown in Fig. 3.

The stem 16 has a vertical portion which is guided by a bracket 17 secured between the magnets, and by an insulating sleeve 18 threaded into the shelf 3. The stem is moved upwardly and downwardly by means of pins 19 secured transversely of the stem, and guided in the slots 20 formed in the armatures 21, which are supported by leaf springs 22 from the washers 23 of the magnets and in operative relation to the latter.

The device is connected to the line wire 24, which is provided with a switch 25, and wire 26 extending to a binding post 27, formed on the end of the spindle 14, at one side of the jar. The other line wire 29 is connected to one terminal of the magnets, the other terminal being connected through a wire 28 to one end of the spindle 8.

In the operation of the rheostat, when the switch 25 is closed, the initial current passes through the wire 26, spindle 14, sleeve 13, and element 12, to the electrode 11. The element being initially in the position shown in Fig. 1, only a minimum amount of current will pass through the liquid in the jar to the electrode 9. The current will pass thence through wire 28 and the magnets 5 and 4, respectively, to the line wire 29. The initial current will energize the magnets sufficiently so that the armatures 21 will be drawn into contact with the cores 30 against the resistance of the springs 22. The stem 16 will thereby be lowered to the position shown in Fig. 3, thus slackening the

cord 15 and permitting the element 12 to gravitate slowly downwardly until it finally reaches the position shown in Fig. 3. The core of the electrode 9 is located within the 5 magnetic field set up by the energization of the electro-magnets, and, particularly after the parts are in the position shown in Fig. 3, where the maximum current will be reached, the magnetic attraction between the 10 electrodes will be sufficient to insure a close, firm contact.

When the switch 25 is opened, the magnets become dead, the armatures are released, and the element 12 is raised again to 15 its initial position. Also, preferably, the springs 22 are made of sufficient strength so that when the voltage in the line reaches a predetermined minimum, they will overcome the attraction of the magnets and act 20 as a cut-out.

The initial amount of current which passes through the magnets when the switch 25 is closed, must be sufficient to energize the magnets enough to overcome the springs 25 22. This amount is obtained by properly regulating the conductivity of the liquid in the jar; for example, for a 2500 watt load, the liquid is so prepared that only 300 watts will pass therethrough, this amount being 30 sufficient to set up a magnetic field that will overcome the springs 22.

From the foregoing description, it will be seen that this invention when placed anywhere in the line, will always insure a gradual introduction of current whenever the switch is turned on. The switch may be located at a remote point, and the action of the rheostat will be entirely automatic and beyond the volition of the operator, and in 40 fact, may be used without his knowledge. The contacts are magnetic, thus insuring a full and complete contact at all times. The container is made of glass, so that its condition can be observed from time to time, and 45 is practically airtight, so that evaporation is prevented and the original liquid should last for many years, since it is hardly disturbed by the operation.

When used in connection with the lamps 50 now in general use, it will prolong the life and brilliance thereof, and will make possible the common use of lamps of higher efficiency than has hitherto been attempted.

When used in connection with electric motors, it will compel a slow and even start, preventing the sudden inrush of current which is destructive to the fuses, and will therefore reduce motor starting troubles to a minimum.

It will also solve the problem which 60 confronts the makers of motion picture lighting apparatus.

The rheostat will, of course, be made in different sizes according to the use for which 65 it is designed, and by making the jar longer,

the number of magnets and likewise the number of elements may be increased as desired. It will also be understood that while I have shown and described one specific embodiment of my invention, the same is capable of many modifications within the scope of the appended claims.

What is claimed is:—

1. In a device of the character described, a pair of electrodes normally separated by a 70 gap filled with liquid of relatively low conductivity and operable by the initial current passing therethrough to completely close the gap and establish a firm contact between the electrodes.

2. In a device of the character described, a pair of electrodes normally separated by a gap filled with a liquid of relatively low conductivity, an electro-magnet energized by the initial current passing through the liquid, 75 and means set in operation by said magnet to completely close the gap and establish a firm contact between the electrodes.

3. In a device of the character described, a pair of electrodes normally separated by a 80 gap filled with a liquid of relatively low conductivity, one of said electrodes being movable by gravity toward the other electrode, and means normally overcoming such gravitation, the initial current through the electrodes being capable of releasing said 85 means to permit the movable electrode to gravitate.

4. In a device of the character described, a pair of electrodes normally separated by a 90 gap filled with a liquid of relatively low conductivity, one of said electrodes being movable by gravity toward the other electrode, means normally overcoming such 95 gravity, and means actuated by the initial current through the electrodes to release the first-named means and permit the movable electrode to gravitate.

5. In a device of the character described, a jar containing liquid, a fixed electrode 100 immersed in the liquid, a second electrode pivotally mounted and normally held above the fixed electrode and adapted when released to gravitate about its pivot towards the fixed electrode, a switch, and means 105 actuated by the turning of the switch to release said pivoted electrode.

6. In a device of the character described, a jar containing liquid, a fixed electrode 110 immersed in the liquid, a movable electrode, a switch, means operable by the closing of the switch to cause the movable electrode to move toward the fixed electrode, and means for causing the movable electrode to move away from the fixed electrode when 115 the voltage of the line falls below a predetermined minimum.

7. In a device of the character described, a jar containing liquid, a fixed electrode 120 immersed in the liquid, a second electrode mov- 125

- able toward and away from the fixed electrode, a switch, and an electro-magnet operable, when the switch is turned on, to cause said second electrode to move toward the fixed electrode.
8. In a device of the character described, a jar containing liquid, a fixed electrode immersed in the liquid, a second electrode movable toward and away from the fixed electrode, a switch, and an electro-magnet operable, when the switch is turned on, to cause said second electrode to move toward the fixed electrode, said fixed electrode being within the magnetic field set up by the electric current and energized thereby.
9. In a device of the character described, a pair of electrodes normally separated by a gap filled with liquid of relatively low conductivity, a switch operable to close the circuit through the electrodes and liquid, an electro-magnet energized by this initial current and operable when energized to close the gap between the electrodes, said magnet being also operable to set up a magnetic attraction between the electrodes when closed.
10. In a device of the character described, a pair of electrodes normally separated by a gap filled with a liquid of relatively low conductivity, one of said electrodes being movable by gravity toward the other electrode, an electro-magnet having a spring-held armature, means actuated by the armature under action of the spring to overcome the action of gravity on the movable electrode, and a switch for turning current through the electrodes, liquid and electro-magnet, the latter when so energized overcoming the action of the spring to permit the movable electrode to gravitate.
11. In a liquid rheostat, a fixed electrode in the form of a separate bar immersed in liquid, a spindle located above and parallel to the fixed electrode and having a binding post at one end, a conductor element loosely mounted on the spindle and having a bar constituting a movable electrode adapted to swing by gravity into contact with the fixed electrode but normally held in its uppermost position, a switch and means actuated by the switch to release the conductor element and permit the same to gravitate until the electrodes form a contact.
12. In a liquid rheostat, a jar containing liquid, a bar supported horizontally in the liquid and forming a fixed electrode, a spindle located above and parallel to the fixed electrode, a conductor element comprising a sleeve loosely mounted on the spindle, and a bar carried by the sleeve and constituting a movable electrode adapted to swing about the spindle into contact with the fixed electrode, spring-held means to normally overcome gravity and hold the conductor element in its uppermost position, a switch and means actuated by the switch to release

- the conductor element and permit the same to gravitate until the electrodes form a contact.
13. In a liquid rheostat, a fixed electrode in the form of a separate bar immersed in liquid, a spindle located above and parallel to the fixed electrode and having a binding post at one end, a conductor element in the shape of a quadrant loosely mounted on the spindle and having a bar constituting a movable electrode adapted to swing by gravity into contact with the fixed electrode but normally held in its uppermost position, a switch and electro-magnetic means operable by the initial current through the liquid when the switch is turned on to release the conductor element and permit the same to gravitate until the electrodes form a contact.
14. In a liquid rheostat, a jar containing liquid, a bar supported in the walls of the jar and forming an electrode immersed in the liquid, a spindle located above and parallel to the bar and having a binding post at one end, a conductor element comprising a sleeve loosely mounted on the spindle, and a bar secured to the sleeve and constituting a movable electrode adapted to swing by gravity about the spindle into contact with the fixed electrode, spring-held means to normally overcome gravity and hold the conductor element in its uppermost position, a switch and electro-magnetic means operable by the initial current through the liquid when the switch is turned on to release the conductor element and permit the same to gravitate until the electrodes form a contact.
15. In a liquid rheostat, a jar containing liquid, a fixed electrode in the form of a separate bar immersed in the liquid and supported by the walls of the jar, a spindle located above and parallel to the fixed electrode and having a binding post at one end, a conductor element loosely mounted on the spindle and having a bar constituting a movable electrode adapted to swing by gravity into contact with the fixed electrode, a stem mounted for vertical movement and flexibly connected to the conductor element and normally holding the latter in its uppermost position, a switch, and means operable by the initial current through the liquid when the switch is turned on to lower said stem and permit the conductor element to gravitate until the electrodes form a contact.
16. In a liquid rheostat, a jar containing liquid, a fixed electrode in the form of a separate bar immersed in the liquid and supported by the walls of the jar, a spindle located above and parallel to the fixed electrode and having a binding post at one end, a conductor element loosely mounted on the spindle and having a bar constituting a

- movable electrode adapted to swing by gravity into contact with the fixed electrode, a stem mounted for vertical movement and flexibly connected to the conductor element and normally holding the latter in its uppermost position, a switch, a pair of electro-magnets in the line connected to one of the electrodes and having spring-held armatures, the normal initial current through the liquid when the switch is turned on being sufficient to close said armatures, and pin-
- and-slot connections between said armatures and said stem whereby the latter is moved downwardly by a closure of the armatures to release the conductor element and permit it to gravitate until the electrodes form a contact.

In testimony that I claim the foregoing as my own, I have hereto affixed my signature.

WILLIAM BLACKNELL CROSSLAND.
